US00D856143S

(12) **United States Design Patent** (10) **Patent No.:** **US D856,143 S**
(45) **Date of Patent:** **** Aug. 13, 2019**

(54) **CLOSURE**

- (71) Applicant: **Closure Systems International Inc.**,
Lake Forest, IL (US)
- (72) Inventors: **Russell Lewis Tartock**, Crawfordsville,
IN (US); **Larry Holmes**, Fishers, IN
(US)
- (73) Assignee: **Closure Systems International Inc.**,
Lake Forest, IL (US)
- (**) Term: **15 Years**
- (21) Appl. No.: **29/653,853**
- (22) Filed: **Jun. 19, 2018**

Related U.S. Application Data

- (63) Continuation of application No. 29/594,645, filed on
Feb. 21, 2017.
- (51) **LOC (12) Cl.** **09-07**
- (52) **U.S. Cl.** **D9/454**

(57) **CLAIM**

The ornamental design for a closure, as shown and described.

DESCRIPTION

FIG. 1 is a top-perspective view of a closure;
FIG. 2 is a side cross-sectional view of the closure taken in the direction of line 2-2 on FIG. 1;
FIG. 3 is a bottom-perspective view of the closure of FIG. 1;
FIG. 4 is a top plan view of the closure of FIG. 1;
FIG. 5 is a left side elevation view of the closure of FIG. 1;
FIG. 6 is a right side elevation view of the closure of FIG. 1;
FIG. 7 is a front elevation view of the closure of FIG. 1;
FIG. 8 is a back elevation view of the closure of FIG. 1; and,
FIG. 9 is a bottom plan view of the closure of FIG. 1.
The evenly broken lines are shown for the purpose of illustrating parts of the article that form no part of the claim.

1 Claim, 4 Drawing Sheets
